CLAIM

The ornamental design for a housing enclosure for a microprocessor controller, as shown and described.

DESCRIPTION

FIG. 1 is a front view of a housing enclosure for a microprocessor controller;

FIG. 2 is a rear view thereof;

FIG. 3 is a top view thereof;

FIG. 4 is a bottom view thereof;

FIG. 5 is a left side view thereof; and,

FIG. 6 is a right side view thereof.

The broken line showing of elements is for illustrative purposes only and forms no part of the claimed invention.
